ANALYSIS OF GASES

John D. Morgan, South Orange, and Alan P. Sullivan, Elizabeth, N. J., assignors, by mesne assignments, to Cities Service Oil Company, New York, N. Y., a corporation of Pennsylvania

Application November 10, 1938, Serial No. 239,794

7 Claims. (Cl. 23—232)

This invention relates to the analysis of gases, and more particularly to apparatus adapted for checking the operating efficiency of domestic and industrial heating furnaces and Diesel engines in accordance with the temperature and composition of gaseous products of combustion discharged therefrom. The apparatus of the present invention is a continuation-in-part of and improvement on that described in our copending application Serial No. 137,168 filed April 16, 1937.

In operating gas analyzing apparatus of the types described in our above-mentioned copending application, ignition of a gas under analysis is effected at the surface of a hot catalytic platinum or platinum-alloy wire forming one leg of a Wheatstone bridge. Any increase in temperature of the wire resulting from catalytic combustion of the gas increases the electrical resistance of the wire by an amount proportional to the combustion constituents in the gas under analysis. The catalyst wires which are used in this type of gas analyzer may have an operating life of several thousand hours if they are not heated to a temperature higher than about 1600° F.—1700° F. However, it has been found that when such catalyst wires are employed in the analysis of gases containing paraffinic hydrocarbons or their derivatives, the catalyst wire gradually suffers a loss in activity at the optimum operating temperature of 1400—1600°. Such loss in activity of the catalyst is apparently the result of poisoning of the catalyst by aldehydes or other intermediate partial oxidation products of such paraffinic hydrocarbons and derivatives. Poisoning of the catalyst can be avoided if the catalyst is operated continuously at a higher temperature in the neighborhood of 2000° F. However, the life of a catalyst wire operating at 2000° F. is extremely short, sometimes being only a few hours.

The primary object of the present invention is to provide improved gas analyzing apparatus which shall be adapted for use in adjusting all such combustion operations as occur in furnaces, Diesel engines, and the like to a condition of optimum operating efficiency with respect to the particular combustion apparatus and fuel under test.

A more specific object of the present invention is to provide gas analyzing apparatus operating by catalytic combustion and so designed as to avoid difficulties with catalyst poisoning heretofore referred to.

Another object of the invention is to provide gas analyzing apparatus designed to avoid any

erroneous readings which might otherwise be obtained as a result of variations in the pressure of the gas to be analyzed at the point where the sample is taken for analysis. With this object in view a feature of the invention contemplates improvement in apparatus whereby the gas to be analyzed and any combustion constituents which are added thereto for the purpose of promoting combustion reactions, are fed to the analyzing unit of the apparatus at a uniform rate.

Essentially the apparatus of the present invention is designed to effect substantially simultaneous measurements of the factors of flue or exhaust gas temperature, amounts of unburned combustible, and amounts of excess oxygen in the flue or exhaust gases under test, at several points on the load curve of the furnace or engine between high and low load. After such measurements are made, the operation of the combustion apparatus under test can then be regulated in accordance with such measurement by proportioning the air and fuel supplies to the furnace or engine so that the temperature of the products of combustion is at a minimum point with the combustion apparatus set at normal operating conditions to meet the average load.

In general, domestic heating furnaces and Diesel engines operate best under a condition of overventilation, wherein the products of combustion leaving the combustion chamber may contain small amounts of unburned combustible and relatively large amounts of excess air. On the other hand, certain industrial furnaces are frequently operated under conditions of under-ventilation, wherein the products of combustion may contain very little if any unreacted oxygen, but relatively large amounts of unburned combustible.

The apparatus of the present invention is designed for use even by an unskilled operator in effecting accurate and substantially simultaneous measurements of the temperature and composition of gaseous products of combustion containing either or both unreacted oxygen and unburned combustible. This apparatus has been particularly designed for making continuous temperature measurements of the flue gas or exhaust gas adjacent the point at which it leaves the combustion chamber, and for the simultaneous removal of a sample stream of exhaust gas at the point of temperature measurement. The gas sample is thereafter divided into two streams, and a uniform portion of each stream is quantitatively analyzed respectively for excess oxygen and for unburned combustible.

With the above and other objects and features in view, the invention consists in the improved apparatus which is hereinafter described and more particularly defined by the accompanying claims.

In the following description of the invention, reference will be had to the attached drawing, in which:

Fig. 1 is a diagrammatic flow sheet of the apparatus assembly showing the gas analyzer and a hydrogen cell in section, and other parts of the apparatus in perspective and elevation; and

Fig. 2 is a wiring diagram.

Referring to Fig. 1, numeral 10 designates a gas sampling tube having an apertured sampling nozzle 12 at its inlet end, said nozzle being adapted for introduction into the exhaust pipe of an engine or the waste gas flue 14 of a furnace for securing a continuous sample of the engine exhaust gas or furnace flue gas to be analyzed. A thermocouple 16 is mounted in flue 14 at a point closely adjacent the point of location of the gas sampling nozzle 12, and lead wires 18 and 20 connect the thermocouple 16 through a switch 22 to a millivoltmeter 24 which is calibrated for measuring the temperature of the flue gases.

Gas which is withdrawn from the flue 14 through the sampling tube 10 is conducted into a gas filter and liquid separator 26. Filter 26 may be filled with copper filings, cotton, glass wool, or other dry filtering material. From filter 26, the gas sample is conducted by a tube 28 to an aperture 30 in the housing or bearing of a rotatably journaled multi-apertured gas flow regulator valve 32. With the valve 32 set in the position illustrated diagrammatically in Fig. 1, all of the gas sample which reaches aperture 30 flows through a peripheral groove 34 in the valve to an aperture 36 in the valve housing, and thence through a conduit 38 by which the gas is conducted to an inlet port 40 of a rotary suction pump 42.

Pump 42 is a rotary sliding vane type pump, and it will be understood that this type of pump normally discharges gas from its discharge port at a rate which varies with variations in pressure at the inlet port 40. For the satisfactory operation of the gas analyzing apparatus of the present invention it is important that so much of the gas sample as is subjected to analysis should be delivered to the analyzing apparatus at a substantially constant rate, irrespective of variations in pressure at the point at which the gas sample is taken. Accordingly the pump 42 has been provided with two discharge ports 44 and 46 spaced about 90° apart in the direction of rotation of the pump. The discharge port 44 is connected directly to an atmospheric discharge orifice 48 and is proportioned to effect discharge of at least three-quarters of the gas introduced to the pump through the inlet port 40. Since the second discharge port 46 handles only the gas which is left within the pump chamber after a major portion of the gas has been discharged by the port 44, that gas which is discharged from the pump through the port 46 leaves the pump at a substantially constant pressure closely approximating atmospheric, and at a substantially constant rate.

The gas which is discharged from the pump 42 through the exhaust port 46 is conducted by a conduit 50 directly to an inlet aperture 52 of a gas analyzer chamber 54. After passing through the chamber 54 the stream of gas which is in-

troduced thereto through aperture 52 exits to atmosphere through a discharge aperture 56.

Analyzer 54 serves, according to the present invention, for the quantitative analysis of the gas sample by combustion to determine the amount of uncombined oxygen carried by the gas. Another analyzer 58 may be simultaneously operated on another part of the gas sample to determine how much uncombined combustible constituents are present in the gas sample.

The sample of gas which is taken by tube 10 may or may not carry both uncombined oxygen and uncombined combustible. A second gas and air mixing pump 60 is accordingly provided which operates to withdraw a minor portion of the original gas sample, mix air at a uniform rate in excess of the amount necessary to burn any uncombined combustible therein, and deliver such air-gas mixture through a conduit 62 to inlet aperture 64 of chamber 58. Inlet or suction port 66 of pump 60 is connected by a pipe 68 with the discharge port 44 of pump 42. Thus a part of the gas which exits from pump 42 through discharge port 44 is withdrawn at a substantially constant rate into pump 60, and is admixed within the pump 60 with air introduced thereto through an atmospheric air inlet port 70. The uniformly proportioned mixture of gas and air thus formed in pump 60 is delivered at a constant rate to the chamber 58 through the discharge port 72 and conduit 62. After passing through chamber 58 the gas is discharged to atmosphere through an orifice 74.

An electrolytic hydrogen generating cell 76 is provided for the purpose of supplying hydrogen at a uniform rate and in sufficient quantity to mix with the sample of gas which is to be analyzed for uncombined oxygen to insure combustion of any oxygen in that portion of the gas sample which contacts the catalyst wire in analyzer 54. The hydrogen cell 76 consists essentially of two electrodes immersed in an electrolyte bath and separated by a diaphragm. Thus cell 76 is provided with an inner cylindrical anode 78 constructed of sheet nickel which is in turn closely surrounded by a cylindrical asbestos cloth diaphragm 80, and diaphragm 80 is in turn surrounded by a cylindrical sheet nickel cathode 82. All of the members 78, 80 and 82 are arranged concentrically within a sealed housing, and each of the electrodes is also immersed in an electrolyte bath consisting of a dilute solution of sodium hydroxide in distilled water.

Hydrogen which is generated in the cell 76 exits therefrom through a pipe 84, while oxygen which is simultaneously liberated by the cell exits from the interior of the anode through a pipe 86. The interior of the cell 76 is completely sealed except for pipes 84 and 86, and these may be closed off, when the cell is not in use, by an apertured valve 88. With the valves 88 and 32 in the positions shown in Fig. 1, oxygen liberated by the cell 76 is discharged to atmosphere through a valve aperture 90. At the same time hydrogen generated by the cell is passed by a valve aperture 92 to the inlet end of a pipe 94. From pipe 94 the hydrogen passes through connecting apertures 96—97—98 in valve 32 and in its housing, which apertures in turn communicate by a pipe 100 with conduit 50; so that the hydrogen is admixed with the gas flowing to analyzer 54 through conduit 50 for the purpose of insuring reaction of uncombined oxygen in the gas sample with the hydrogen.

With the valve 32 turned clockwise 90° from

the position shown in Fig. 1 to a new position which is not illustrated, the gas sample is deflected to atmosphere through the groove 34 in the valve; and, in place of gas, air is conducted to the inlet port 40 of pump 42 from an air supply pipe 102 through a peripheral groove 104 in valve 32, and thence through conduit 38. With the valve 32 in the position under discussion, any hydrogen which is delivered to the valve 32 by pipe 94 is exhausted to atmosphere through a peripheral groove 106 and a relief aperture 108. Thus with the valve in this position only air is handled by the two pumps 42 and 60, and only air is passed through the two combustion chambers 54 and 58.

With the valve 32 turned 90° counterclockwise from the position illustrated in Fig. 1 to another new position (not illustrated), the instrument is set at the position for calibrating the analyzer 54 for the temperatures developed by reacting the uniform supply of hydrogen furnished by the electrolytic cell 76 with air. Thus with the valve in this position the gas sample is bypassed to atmosphere through peripheral groove 104, and air only is supplied to the pump 42 through air intake pipe 102, groove 34 and pipe 38. Also with the valve in this position, hydrogen is admixed with the air delivered by pump 42 to cell 54, the hydrogen being in this case conducted from the hydrogen cell through pipe 94, groove 110, housing groove 97, groove 112, and thence to conduit 50 through pipe 100.

Valve 88 has only two normal positions. In the position illustrated in Fig. 1 the valve is open to pass hydrogen from the hydrogen generator to the apertures of valve 32. With the valve 88 turned 90° clockwise from the position illustrated in Fig. 1, the hydrogen generator cell is completely sealed. The stem of valve 88 is equipped with a handle and with a coil spring 113 which is under tension when the valve is in the position illustrated in Fig. 1, such tension tending to rotate the valve clockwise 90° from the position illustrated. An electric switch 114 is operatively connected to the stem of valve 88 by a pivoted pawl 116, the purpose of this hook-up being to insure that when switch 114 opens the circuit supplying current to energize the hydrogen generator cell 76, the pawl 116 simultaneously unlocks valve 88 from the position illustrated in Fig. 1 and permits rotation of the valve in a clockwise direction under the tension of spring 113, thereby sealing the hydrogen generator cell against escape of gas or liquid therefrom through either of the pipes 84 and 86.

The gas analyzers 54 and 58 are embodied in a unitary housing comprising a block of dielectric heat insulating material. Centrally apertured dielectric plugs 118 form quickly detachable bottom closures for each of the chambers 54, 58, extending upwardly into the respective chamber. Each of these plugs in turn carries at its top a plurality of upright wire supporting rods 119. These rods also form connecting leads for electrically heated catalyst wires 120-122, which are mounted respectively in the chambers 54 and 58. The catalyst wire 120 forms one leg of a Wheatstone bridge of which another non-catalyst leg is designated by the numeral 124. Legs 120 and 124 are mounted in spaced horizontal parallel relation within chamber 54. The other two legs of this Wheatstone bridge are designated in Fig. 2 by the numerals 126 and 128. The analyzer 54 is designed to measure amounts of uncombined oxygen up to ten per cent by 76

volume in the products of combustion under analysis. The catalyst wire 120 may for example consist of a wire of platinum-5-per-cent-iridium alloy, $\frac{1}{16}$ inch in length and .0035 inch in diameter. The wire 126 should have the same diameter and length as the wire 120. The wires 124 and 128 may be platinum-5-per-cent-rhodium alloy wires $\frac{1}{16}$ inch in length and gold plated to a final diameter of .0038 inch. A bridge embodying wires of the dimension and composition stated will stand up for long periods when operated at temperatures in the range 1400-1600° F., and the conductivities of the legs of the bridge remains substantially balanced when operating in the specified temperature range in air.

The catalyst wire 122 in chamber 58, together with a balancing catalyst wire 130 (see Fig. 2) may both be constructed of $\frac{1}{16}$ inch lengths of platinum-five-per-cent-iridium alloy wire .0035 inch in diameter. Balancing non-catalyst legs 132-134 in the same bridge may be constructed of $\frac{1}{16}$ inch lengths of platinum-five-per-cent-rhodium alloy wires .0035 inch in diameter, which latter wires have a nickel oxide coating. Catalyst wire 122 and non-catalyst wire 132 are mounted in spaced parallel relation within analyzer 58.

The central apertures 52 and 64 in the respective plug closures 118 at the lower ends of the chamber 54 and 58 communicate at their lower ends with the respective gas supply pipes 50 and 62, and at their upper ends communicate through radial apertures 136 with the interiors 35 of the respective chambers 54 and 58. The catalyst and non-catalyst wires in the respective combustion chambers are enclosed within cylindrical metal shields 138 which are open at the top and which are closed at the base by the tops 40 of the plugs 118. A fine mesh metal screen 140 is disposed transversely as a closure within each shield 138 at a point closely spaced above the respective catalyst wires 120 and 122. Any gas flowing through the respective combustion chambers 54 and 58 can only come into contact with the respective catalyst wires 120 and 122 by diffusion and convection through the metal screens 140. According to the preferred design, the shields 138 are dimensioned with approximately 50 $\frac{1}{2}$ inch internal diameter, so that the catalyst wires are closely surrounded on all sides by metal.

An important construction feature of the gas analyzer herein described resides in the means 55 employed for avoiding difficulties heretofore encountered with catalyst poisoning. Among the principal elements contributing to this result are the metal screens 140 (for example, 100 mesh Monel metal screen) located in closely spaced 60 heat transfer relation to the electrically heated wires 120, 124, 122 and 132, where the screens function as gas preheaters to preheat the gas mixtures under analysis, prior to contact with the catalyst surface, to a temperature in the range 650° F.-1200° F. It has been found that by thus preheating the gas mixture under analysis either by means of the screens 140 or by other independently operated preheating elements such as for example electrically heated wire coils or preheating chambers, catalytic poisoning of almost any normally catalyst poisoning combustible constituent can be effected at the optimum temperature range of 1400-1600° F. without difficulty with poisoning.

In order to insure against poisoning of the

catalyst in analyzing any gas, the analyzer herein described may be provided with another means of inhibiting poisoning; said means consisting of a coating of alkaline earth oxide applied to one or both of the catalyst wires 120, 122. Application of such a coating to the wires has the effect of increasing the electron emission rate at temperatures above 300° F. It is important that the oxide coating be applied in such a way that it will not be blown off by immersion of the coated wires in a moving current of hot gas. The coating is preferably applied to a wire by enclosing the wire in a chamber while passing electric current through the wire to heat it to a high temperature (yellow heat), and while the chamber is filled with a dust cloud or atmosphere containing approximately 90 per cent barium oxide and ten per cent cerium oxide. The dust cloud is made up of particles ground to a fineness greater than 300 mesh. Some of the dust settles on, or is directed to, the surface of the wire and is apparently affixed thereto by chemical action at the high temperature at which the wire is coated. After cooling the wire, the coated wire is subjected to a further heat treatment in an atmosphere of reducing gas containing for example up to five per cent hydrogen and 95 per cent nitrogen, or in an atmosphere consisting primarily of combustible gas. This treatment of the oxide coated wire in a reducing atmosphere seems to definitely improve and affix the coating in a way in which it is not affixed by the first heating and coating treatment. Other alkaline earth oxide coatings have been successfully used, including coatings of barium oxide, cerium oxide, strontium oxide and thorium oxide.

The rotors of pumps 42 and 60 are keyed to the drive shaft of electric motor 75. Motor 75 is powered by current supplied by an electric circuit 142 controlled by a switch 114; and the electric energy for heating the catalyst wires 120 and 122 of the gas analyzer is also taken from the circuit 142, the voltage being reduced by a transformer 144 to an approximate value of about 5.5 volts. As shown in Fig. 2, provision is made for supplying current at a constant rate from the low voltage side of the transformer 144 to both sides of the gas analyzer, as well as to the hydrogen cell 76. To accomplish this the current flows from the low voltage side of the transformer to a pair of full wave bridge rectifiers 146-148, through an adjustable rheostat 150. The rectified D. C. current of approximately 2.4 amperes is taken from secondary points on the rectifiers 146-148, to points 152-154 of the respective Wheatstone bridges embodying as legs catalyst wires 120 and 122. The current flowing through each of the Wheatstone bridges is controlled by zero adjustment rheostats 156-158 which are connected in shunt circuit respectively across the catalyst legs 120 and 122. The fixed resistances 126-128-130 and 134 are preferably mounted on spools secured within the analyzer units, and may be balanced as to dimensions and composition with the corresponding legs 120-124-122 and 132. The rheostats 156-158 are employed for adjusting the initial or zero electrical balance of the bridges embodying the catalyst legs 120, 122 respectively.

The double pole double throw switch 22 is used to alternatively connect millivoltmeter 24 either with the thermocouple 16 through leads 18 and 20 or with the Wheatstone bridge embracing catalyst 122 as one leg. Thus the millivoltmeter 24 is provided with two scales, one of which is

calibrated to measure temperatures obtaining in flue 14, while the other scale is calibrated to measure percentages of combustible gas in the gas stream flowing through analyzer chamber 58 and in contact with catalyst wire 122. A corresponding millivoltmeter 160 is operatively connected across the Wheatstone bridge embracing catalyst wire 120 as one leg, and is calibrated to measure percentages of uncombined oxygen in the gas which passed through the excess oxygen analyzer 54.

It might be expected that the excess oxygen analyzer 54 would operate best when the volume of hydrogen which is admixed with the gas sample passed therethrough is proportioned to the volume of gas in the ratio of one unit of hydrogen for each half unit of oxygen in the gas under analysis. Experience has shown, however, that in operating a gas analyzer having the optimum dimensions and construction previously referred to, at an optimum temperature in the range 1400-1600° F., the most accurate readings on the percentage of excess oxygen in the gas under analysis have been obtained when the volume ratio of added hydrogen to oxygen in the gas sample passed through the excess oxygen analyzer, is approximately 1:1. With this volume ratio of hydrogen to oxygen the analyzer is operative for giving accurate quantitative measurements of amounts of excess oxygen up to 20 per cent by volume of the gas under analysis.

Having thus described the invention in its preferred form, what is claimed as new is:

1. A gas analyzer for quantitatively measuring a combustion constituent in a gas comprising a vertically disposed combustion chamber, means for passing a continuous stream of gas to be analyzed at a uniform rate upwardly through the chamber, a metal cup mounted centrally within the chamber with imperforate base and side walls positioned in baffling relation to the stream of gas flowing therethrough, a Wheatstone bridge electric circuit embodying a catalyst wire leg and a non-catalyst wire leg of approximately balanced electrical conductivity mounted in closely spaced parallel relation within said cup, and a preheater mounted in the path of gas flowing downwardly through the open end of the cup toward said catalyst and non-catalyst legs.

2. Apparatus as defined in claim 1, in which the preheater comprises a multi-apertured metal screen disposed as a closure at the open end of said cup at a spaced distance of not to exceed $\frac{1}{4}$ inch from the catalyst and non-catalyst wire legs.

3. A gas analyzer for quantitatively measuring a combustion constituent in a gas comprising a combustion chamber, means for passing a continuous stream of gas to be analyzed at a uniform rate upwardly through the chamber, a metal cup mounted centrally within the chamber with imperforate base and side walls positioned in baffling relation to the stream of gas flowing therethrough, and a Wheatstone bridge electric circuit embodying a catalyst wire leg and a non-catalyst wire leg of approximately balanced electrical conductivity mounted in closely spaced relation within said cup, said catalyst wire leg having a coating of alkaline earth oxide fixed thereto by heat in a reducing atmosphere.

4. In analyzing gas to determine the amount of oxygen therein up to 20% by volume, the steps comprising passing a continuous stream of the gas upwardly through a combustion chamber admixing hydrogen with the gas prior to its en-

trance to the chamber in amount sufficient to provide a hydrogen-oxygen volume ratio in the mixture less than 2:1, passing electric current through a metal catalyst wire within said chamber in amount sufficient to heat said wire to a temperature above the ignition temperature of said hydrogen-oxygen constituents, baffling the gas stream against direct flow contact with the catalyst wire, allowing some gas from the stream to reverse direction of flow to contact the catalyst solely by diffusion and convection, and preheating the gas prior to contact with the catalyst to a temperature in the range 650° F. to 1200° F.

5. In analyzing a gas to determine quantitatively amounts of oxygen therein up to 20 per cent by volume of the gas, the steps comprising passing a continuous stream of the gas at a uniform rate through a combustion chamber, admixing with the gas prior to its entrance to the combustion chamber a continuously flowing hydrogen stream in the proportion to provide a hydrogen to oxygen volume ratio in the mixture of approximately 1:1, heating a catalyst wire within said combustion chamber by passing therethrough an electric current in amount sufficient to heat said wire to a temperature in the range 1400-1600° F. when immersed in air, and baffling the gas stream against direct flow contact with the catalyst wire, while allowing some gas from the stream to reverse direction of flow to contact the catalyst solely by diffusion and convection.

6. A gas analyzer adapted for quantitatively measuring the amount of oxygen in a gas comprising a combustion chamber, means for passing a continuous stream of gas to be analyzed at a uniform rate through the chamber, a metal cup mounted centrally within the chamber having

imperforate base and side walls positioned in baffling relation to the stream of gas flowing therethrough, a Wheatstone bridge electric circuit embodying a catalyst wire leg and a non-catalyst wire leg of approximately balanced electrical conductivity mounted in closely spaced parallel relation within said cup, a preheater mounted in the path of a fraction of the main gas stream flowing in reverse direction through 10 the open end of the cup toward said catalyst and non-catalyst legs, an electrolytic hydrogen generator cell operatively connected to continuously add to said gas stream prior to its entrance to the chamber a uniformly proportioned increment 15 stream of hydrogen, and means for supplying energizing current at a controlled rate both to the hydrogen generator and to the Wheatstone bridge circuit.

7. A gas analyzer for quantitatively measuring the amount of oxygen in a gas comprising a combustion chamber, means for passing a continuous stream of gas to be analyzed at a uniform rate through the chamber, an electrolytic hydrogen cell connected for continuously adding to said gas stream prior to its entrance to the chamber a uniformly proportioned increment 20 stream of hydrogen, a pair of conduits leading off from said cell and adapted respectively for removal of hydrogen and oxygen therefrom, an electric switch for controlling supply of electric current to the hydrogen cell, and means operatively connected with the switch for automatically preventing release of gas and electrolyte liquid from the cell through said conduits during 25 30 33 periods when the switch is open.
